UNITED STATES PATENT OFFICE

WERNER SCHULEMANN, OF VOHWINKEL, NEAR ELBERFELD, AND FRITZ SCHÖNHÖFER AND AUGUST WINGLER, OF ELBERFELD, GERMANY, ASSIGNEES TO WINTHROP CHEMICAL COMPANY, INC., OF NEW YORK, N. Y., A CORPORATION OF NEW YORK

PROCESS FOR THE MANUFACTURE OF 6-ALKOXY-8-AMINOQUINOLINES

No Drawing. Application filed January 21, 1928, Serial No. 248,562, and in Germany January 26, 1927.

The present invention is a modification of the process protected in the specification Ser. No. 85,030 filed January 30, 1926 for the manufacture of 6-alkoxy-8-aminoquinolines, and consists in subjecting 6-alkoxy-
5 quinoline-8-carboxylic acid esters to the Curtius reaction, as will be hereinafter more fully described, that is to say by treating the esters with hydrazine hydrate to form
10 the hydrazides, treating the latter with nitrous acid to form the azides, treating the azides with an alcohol to obtain the urethanes and treating the urethanes with a saponifying agent, e. g. with acids or alkalies,
15 to obtain the amines. The reaction proceeds according to the following scheme:

stands for a quinoline radicle, R_1 for an alkyl, aryl or aralkyl radicle.

In accordance with the specification Serial No. 85,030, 6-alkoxy-8-aminoquinolines are produced by reducing by the customary methods 8-nitro or 8-azo-derivatives of 6-
25 alkoxyquinolines or by alkylating 6-hydroxy-8-aminoquinoline or its N-substitution products on the hydroxyl oxygen and if desired converting the derivatives of 6-
30 alkoxy-8-aminoquinolines thus obtainable, which are substituted in the nitrogen atom into the free amino compound.

In accordance with the present invention the same compounds can also be produced in a technically excellent manner from 6-alkoxyquinoline-8-carboxylic acid alkyl esters according to the Curtius reaction, as already indicated.

The following example will illustrate our invention:

Example.—10 grams of 6-methoxyquinoline-8-carboxylic acid ethyl ester, melting at 62 to 63° C., are heated under reflux for 3 hours with 10 grams of alcohol and 5 grams
45 of hydrazine hydrate. After cooling the

hydrazine, which separates out, is filtered off; its melting point is 178 to 179° C. 4.3 grams of this hydrazide are dissolved in 50 cc. of normal hydrochloric acid and 14 cc. of 10% sodium nitrite solution are slowly added, the whole being cooled in ice. The azide precipitates and after being rendered alkaline is extracted with ether. The ethereal solution is dried with calcium chloride and an equal volume of absolute alcohol is added thereto, when the mixed solution is evaporated on the water-bath to a quarter of the total volume. When the evolution of nitrogen has ceased the evaporation is completed to dryness. The urethane derivative has a melting point of 76 to

77° C. The urethane is mixed with 4 times the quantity of slaked lime and distilled. 6-methoxy-8-aminoquinoline comes over, identical with the corresponding product of the specification Ser. No. 85,030.

We claim:

1. In the process for the manufacture of 6-alkoxy-8-aminoquinolines, the step which comprises subjecting 6-alkoxyquinoline-8-carboxylic acid esters to the Curtius reaction by treating them with hydrazine hydrate to form the hydrazides, treating the hydrazides with nitrous acid to obtain the azides, treating the azides with an alcohol to obtain the urethanes and treating the urethanes with a saponifying agent to obtain the amines.

2. In the process for the manufacture of 6-methoxy-8-aminoquinoline, the step which comprises subjecting 6-methoxyquinoline-8-carboxylic acid esters to the Curtius reaction by treating them with hydrazine hydrate to form the hydrazides, treating the hydrazides with nitrous acid to obtain the azides, treating the azides with an alcohol to obtain the urethanes and treating the urethanes and treating the

urethanes with a saponifying agent to obtain the amine.

3. In the process for the manufacture of 6-methoxy-8-aminoquinoline the step which comprises subjecting 6-methoxyquinoline-8-carboxylic acid ethylic ester to the Curtius reaction by treating it with hydrazine hydrate, to form the hydrazide, treating the hydrazide with nitrous acid to obtain the azide, treating the azide with ethyl alcohol to obtain the urethane and treating the urethane with slaked lime to obtain the amine.

In testimony whereof we have hereunto set
15 our hands.

WERNER SCHULEMANN.

FRITZ SCHÖNHÖFER.

AUGUST WINGLER.
